[57] ABSTRACT

A portable knockdown but self-standing tripodal base provides a stand for an accompanying composite upright having unique vertically spaced holders for readily applicable and removable fresh-cut evergreen boughs or limbs. Each holder embodies a pair of smooth dished disks properly paired and nested with requisite nicety one within the other to grippingly press and clamp the inner ends of the tree-building limbs. These limbs are selectively and carefully coordinated to provide an artificial bushy Christmas tree shaped as desired. The (1) stand and (2) sectional upright or trunk are structurally and functionally novel.

Fig. 1

CHRISTMAS TREE ASSEMBLY

This invention relates to certain new and useful improvements in an artificial Christmas tree which is such in construction and adaptability that the foliage thereof is made up of carefully selected hand-attached boughs or limbs, more particularly, properly sized and balanced limbs which have been cut from live evergreen pine or equivalent holiday trees.

Persons conversant with the field of invention herein disclosed are aware that many and various types of artificial and imitation Christmas trees have been devised and are in widespread use. As a matter of fact, stand-supported sectional uprights and trunks have been employed by others in providing trees of varying heights and wherein the branches (limbs and boughs) are those which have been removed from live trees.

For background information attention is here directed to U.S. Pat. No. 904,758 granted to H. R. Cropp which discloses a display stand for an artificial Christmas tree characterized by a portable knockdown base or stand supporting a complementary upright constructed from separably joined sections carrying co-acting pairs of dished, but corrugated, limb supporting and clamping disks. As further exemplary of the state of the art the reader may also take into account the simulated Christmas tree disclosed in U.S. Pat. No. 3,159,523 granted to A. Abramson, and showing oblique angled socket-type individual branch holders.

The present invention has to do with an adaptation wherein boughs of carefully selected and suitable relative length and appropriateness are capable of being clampingly and selectively mounted on the trunk to provide a tree which well serves the purposes for which it is intended. To the ends desired, and instead of relying on hand pressure to mount and secure the branches, smooth concave-convex or dished disks are utilized for reception and anchoring of the branch-ends to, in this manner, clampingly crush the branch-ends between the smooth-finished disk surfaces and, in so doing, causing the clenched ends to be effectually sealed off. Experience has shown that this sealing off accomplishment virtually eliminates weeping. It follows that the loss of moisture is reduced to a minimum, thus adding to the durability and prolonged life of this unique tree.

In addition, the hereindisclosed stand-type base is strong and durable and embodies an attachable and detachable wrench which is readily available and lends itself to use when erecting and uniting the readily separable and connectible components and the oriented screw-threaded stem or trunk.

Briefly, one aspect of the over-all concept has to do with a knock-down portable base which is fashioned into a novel stand. A tube or sleeve is vertically disposed and has its lower end aligned with a hole provided therefor in a horizontal base plate. The base plate is preferably triangulate in plan and the corner portions are provided with seats for stabilizing components of circumferentially spaced equidistant V-shaped leg frames. The individual inwardly diverging legs are provided with laterally bent terminals which constitute hook-like retainers and which are releasably engageable in socket members provided therefor on the outer surface of collars attached to upper and lower ends of the hub-like sleeve.

More particularly, the concept has to do with a stand which serves to accommodate at least one screw-

threaded shaft or stem. This shaft extends through main and auxiliary sleeves which when assembled provide the desired composite trunk. The trunk includes vertically spaced properly paired holders for the attachable and detachable evergreen boughs or limbs. For best results paired smooth-surfaced disks are dished and nested together and centrally apertured to accommodate the screw-threaded shaft and the coacting main and auxiliary sleeves are so arranged and held by clamping nuts that the paired disks can be firmly clamped together to assemble and retain the natural boughs or limbs in cooperating tree-forming relationship. Thus the stand and trunk is of knock-down construction and capable of being used over and over and the boughs or branches are carefully applied and arranged to conveniently serve the needs of the user during the holiday season.

These together with other objects and advantages which will become subsequently apparent reside in the details of construction and operation as more fully hereinafter described and claimed, reference being had to the accompanying drawings forming a part hereof, wherein like numerals refer to like parts throughout.

FIG. 1 is a view in side elevation of an artificial Christmas tree constructed in accordance with the principles of the present invention and showing the same set up for use with an optional shaft shown as the upper portion of the trunk.

FIG. 2 is an enlarged fragmentary detail section showing component portions of the composite trunk, more particularly, parts of main and auxiliary sleeves, clamping and assembling nuts, and paired concavo-convex disks which are used in perfecting the desired limb or bough holders.

FIG. 3 is a horizontal section taken approximately on the plane of the section line 3—3 of FIG. 2.

FIG. 4 is an exploded perspective view wherein significant essential component parts are shown in ready-to-assemble relationship.

FIG. 5 is an exploded perspective view showing how with the use of an adapter or reducer coupling adjacent ends of main and auxiliary shafts or shaft sections may be united where the height of the tree calls for the use of two or more screw-threaded shafts.

Referring now to the views of the drawings, and particularly to the knockdown base or tree stand attention is directed to FIG. 4. A significant part of this stand comprises a horizontal substantially triangular base plate 6 having a central shaft or stem hole 8 and having each corner portion 10 provided with upstanding spaced parallel triangular flanges or ears 12 which provide stabilizing and assembling members for the leg frames. The over-all stand is referred to as tripodal and preferably embodies three interchangeable leg frames. Each leg frame is the same in construction, is denoted by the numeral 14, and is V-shaped in side elevation. The lower horizontal leg member 16 is adapted to reside flatwise and firmly atop the base plate 6 and has an upturned or laterally directed hook-like terminal 18. The upwardly sloping leg member 20 is likewise provided with a lateral terminal 22 and these hook-like terminals are releasably engageable in terminal anchoring keepers 24 provided therefor on the peripheral surface of a collar. There are two collars, one at the bottom as at 26 and one at the top 28 of a main vertical hub-like sleeve 30. This sleeve constitutes a component part of the composite trunk and the lower open end in practice

rests atop the plate and is lined up with the aforementioned hole 8. When the parts are put together the leg frames fit in place and are retained in associate relationship as brought out in the complete ready-to-use stand or base as shown in FIG. 1. A further and significant component of the trunk or upright comprises the aforementioned screw-threaded vertically disposed stem or shaft 32 the lower portion of which extends down through and beyond the sleeve 30 and in fact below the level of the plate 6 where it is provided with an assembling and retaining nut 34. As is more clearly evident in FIG. 2 a first assembling and clamping nut is provided at 36 and bears against a washer 38 which resides flatwise on the upper end portion 40 of the primary sleeve 30. Thus with these two nuts 34 and 36 the sleeve is connected to and rises perpendicularly from the horizontal plate 6. When it is in place the leg frames 14 can be readily attached or removed as the case may be.

With further reference to FIG. 2 in particular it will be seen that any suitable number of auxiliary sleeves are provided to assist in making up the over-all or composite upright or trunk. Each secondary or auxiliary sleeve is relatively short and as shown in FIG. 2 it is denoted by the numeral 42. It has a bell-like or flaring lower end 44. The upper straight across end is denoted at 46 and this end serves to accommodate a second assembling nut 48 which in practice (not shown) could be integral with said upper end. When the nut 48 is tightened down it functions to assemble and properly retain the paired disks which go to make up each holder. Each disk is of concavo-convex or dished form. An upper disk is denoted at 50 and a companion lower disk at 52. These disks are smoothly made and nested in companion relationship as illustrated in FIG. 2. The centrally apertured portions 54 of the disks surround the screw-threaded shaft 32. When the disks are properly put together they serve to squeezably anchor and clampingly bind and maintain the inner end portions 56 of the boughs 58 (natural limbs or branches). To the ends desired and considering but a single holder it will be evident that the disks 50 and 52 are nested together and sandwiched between the nut 36 and the flared nut-held end 44 of the auxiliary sleeve 42. Since all of the holders are the same in construction a description of one will suffice for all. Accordingly by considering the detailed description just given with reference to FIG. 2 and further considering the exploded view in FIG. 4 and the finished or assembled view in FIG. 1 it is evident that the construction of the knockdown tripod stand should be clear. In addition the composite trunk is believed to be clear. In fact it will be evident that by the use of the carefully selected and cut as well as fresh boughs or limbs 58 an ideal artificial tree is attainable. With this invention and the use of boughs forest areas can be systematically cleaned up. The selector or collector merely selects fresh green boughs from older growing trees and trims them off. In doing this he is clearing the forest floor for game feeding, light for grasses and plants, not to mention new growing trees for future years. He also achieves a reduction in insect breeding and many other advantageous results that contribute to the trimming of the lower branches of the older mature trees for the usable Christmas tree boughs. Then, too, the costs of boughs for a tree are much less than having to purchase a whole tree, as is evident. Further, with this ready-to-erect trunk and

stand members of the family are able to get together and erect a well-balanced and bushy tree on the spot. When the holiday season is over the readily detachable limbs and boughs can be removed, bundled up and conveniently disposed of in a manner to virtually eliminate fire hazards. The stand and trunk can be stored in erect form or taken down and the separate parts put away for more convenient and compact storage requirements as the case may be. Whenever necessary or desired to extend the height of the tree this can be accomplished by employing a smaller and extended shaft such as the one shown at 60 in FIG. 1. To the ends desired an adapter 62 (FIG. 5) can be employed. The adapter comprises component parts 64 and 66 to accommodate and provide sockets 68 for end portions 70 and 72 of the then aligned shafts 32 and 60 respectively.

In actual practice it may be desirable as shown in FIG. 1 to provide a suitable and readily available double-ended wrench 74 which is held in place on the sleeve 30 by an attaching and retaining clip 76. This wrench is made so that the ends can be selectively used to accommodate the fittings and nuts shown in the views of the drawing. The use of this special purpose wrench well serves the purposes for which it has been adopted.

The construction and the arrangement of the parts is believed to be substantially self-evident from the views of the drawing. Accordingly, a more extended description is deemed to be unnecessary.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An artificial Christmas tree comprising a portable self-standing stand, upright means having a lower end attached to and rising perpendicularly above the level of said stand and terminating in an upper end at a predetermined height, said upright simulating the trunk of a tree and embodying at least one pair of face to face assembling and clamping disks between which terminal inner ends of a plurality of companion tree limbs are inserted and forcibly and clampingly held in a manner that the branches radiate beyond the trunk in tree-forming relationship, and manually regulatable mechanical clamping means operably and accessibly embodied in said upright means and functioning to releasably clamp said disks, said disks being concavo-convex, smooth-surfaced and having uninterruptedly smooth concave sides facing upwardly, and wherein said limbs are fresh evergreen boughs cut from natural pine trees.

2. The tree defined in and according to claim 1, and wherein said upright means is of sectional knockdown form and said stand is likewise of sectional knockdown construction, whereby when the set up tree has served its temporary display purposes, it can be dismantled and its component parts compactly and conveniently stored for future erection and use.

3. The tree defined in and according to claim 2, and wherein said stand is tripodod and comprises a horizontal base plate which is centrally apertured, a vertical primary plate-supported axial sleeve having a lower

end resting atop said plate in line with said aperture, circumferentially spaced V-shaped leg frames having horizontal leg members residing flatwise and firmly atop said plate and upwardly inwardly angled toward an upper end of said sleeve, keepers carried by the respective upper and lower end portions of said sleeve, the inner diverging ends of said leg members having lateral hook-like retainers releasably fitted into their respectively cooperable keepers, the outer converging ends of said leg members being joined by substantially semi-circular bent portions and said bent portions defining floor engaging feet.

4. The tree defined in and according to claim 3, and wherein said plate is substantially triangular in plan, the respective apical corners of said plate having pairs of spaced parallel upstanding ears defining stirrup-like seats, and cooperating leg members of the respectively associated horizontal leg members being retentively lodged in cooperable seats.

5. The tree defined in and according to claim 2, and wherein the sections of said upright means comprise a lower main sleeve and upper and intermediate auxiliary sleeves arranged in end-to-end alignment, a single screw-threaded shaft passing downwardly through and stringing all of the sleeves together in coacting alignment, said clamping disks being centrally apertured and interposed between adjacent ends of said predetermined sleeves, and assembling and retaining nuts operatively mounted on predetermined portions of said shaft in a manner to coact with and retain said disks in set positions at will.

6. An artificial Christmas tree comprising, in combination, a portable self-standing tripodal stand embodying a leg and foot supported horizontal base plate hav-

ing an axial shaft opening, a single vertically elongated screw-threaded shaft having a lower end passing downwardly through said hole and held partly in place by an attached holdown nut clamped against an underneath side of said plate in alignment with said shaft opening, a primary sleeve surrounding a cooperating lower portion of said shaft and having a lower end resting firmly atop said plate, a first assembling and retaining nut screwed on said shaft and clampingly cooperable with an upper end of said sleeve, an auxiliary sleeve surrounding a portion of said shaft in a plane above said first assembling nut, a pair of companion dished disks, said disks being wholly smooth-surfaced and having centrally apertured portions encircling said shaft between said first nut and a lower end of said auxiliary sleeve and adapted to permit the inner ends of cut tree limbs to be inserted and clampingly held in a prearranged manner, and a second assembling and clamping nut cooperable with auxiliary sleeve and also screwed on said shaft and coordinated with a coacting upper end of said auxiliary sleeve in a manner to squeezably bind said disks against the clampable inner ends of said limbs.

7. The tree defined in and according to claim 6, and wherein the upper and lower ends of said primary sleeve are encircled by fixedly mounted collars, the outer peripheral surfaces of said collars having equidistant circumferentially spaced keepers, said legs being V-shaped in said elevation and the free divergent ends of the individual legs having laterally bent terminals providing hook-like retainers, and the respective retainers being aligned with and detachably engaged with their respectively cooperable keepers.
